CLAIM

The ornamental design for a recessed power cable transition panel as shown and described.

DESCRIPTION

FIG. 1 is a front, right, top perspective view of a recessed power cable transition panel showing our new design;
FIG. 2 is a rear, left, top perspective view thereof;
FIG. 3 is a front view thereof;
FIG. 4 is a rear view thereof;
FIG. 5 is a top plan view thereof;
FIG. 6 is a bottom plan view thereof; and,
FIG. 7 is a right side view thereof, which is the same as a left side view thereof.

(Continued)

The broken lines depict portions of the recessed power cable transition panel that form no part of the claimed design.

1 Claim, 7 Drawing Sheets
